[57] CLAIM

The ornamental design for floatable signal light, as shown and described.

DESCRIPTION

FIG. 1 is a perspective view of a floatable signal light showing my new design;

FIG. 2 is an elevational view of FIG. 1;

FIG. 3 is an elevational view taken at 90° to FIG. 2;

FIG. 4 is a bottom plan view of FIG. 2;

FIG. 5 is a top plan view of FIG. 2;

FIG. 6 is a perspective view, similar to FIG. 1, showing an upper modified portion;

FIG. 7 is an elevational view, similar to FIG. 2, showing the upper portion of FIG. 6;

FIG. 8 is a perspective view, similar to FIG. 1 showing a modified, intermediate float;

FIG. 9 is a perspective view, similar to FIG. 1, showing still another modified intermediate float;

FIG. 10 is a perspective view, similar to FIG. 1, showing yet another modified intermediate float; and

FIG. 11 is a perspective view, similar to FIG. 1, showing a still further modified intermediate float.

FIG. 1

FIG. 2

FIG. 3

FIG. 4

FIG. 5
